UNITED STATES PATENT OFFICE.

MIKE DEAK, OF CUDDY, PENNSYLVANIA.

RAIL-JOINT JACK.

1,204,850.

Specification of Letters Patent. Patented Nov. 14, 1916.

Application filed February 16, 1916. Serial No. 78,707.

To all whom it may concern:

Be it known that I, MIKE DEAK, a citizen of the United States, residing at Cuddy, in the county of Allegheny and State of Pennsylvania, have invented certain new and useful Improvements in Rail-Joint Jacks, of which the following is a specification, reference being had to the accompanying drawings.

10 This invention relates to an improved rail joint jack and has for its primary object to provide a simple, durable and serviceable device for loosening the fish plates at the rail joints so that the rail sections 15 can be readily removed.

It is a more particular object of the invention to provide a jack of the above character for operating upon a boltless rail joint or splice of that character wherein the fish 20 plates are integrally formed with the chair plate, said device including a stationary part adapted to be clamped upon one of the rails, a movable element adapted to be connected to the joint member, and means 25 for actuating said movable element.

It is another general object of the invention to simplify and improve the construction of a jack for the above purpose and enable the same to be easily and quickly 30 arranged in operative position, the device as a whole being capable of manufacture at relatively small cost.

With the above and other objects in view, my invention consists in the novel features 35 of construction, combination and arrangement of parts to be hereinafter more fully described, claimed and illustrated in the accompanying drawing, in which.

Figure 1 is a side elevation showing my 40 improved rail joint jack arranged in position upon the rail; Fig. 2 is a section taken on the line 2—2 of Fig. 1; Fig. 3 is a section taken on the line 3—3 of Fig. 1; and Fig. 4 is a detail fragmentary perspective 45 view of the movable rack bar.

Referring in detail to the drawing, 5 designates the body of the jack which is in the form of an elongated integral casting having a longitudinally extending rectangular bore 6. Upon one end of this casting and from opposite sides thereof, the downwardly diverging foot members or braces 7 obliquely extend and have their lower end faces toothed or serrated for biting engagement into the surface of a tie indicated at T, as clearly shown in Fig. 1.

A rack bar 8 is longitudinally movable through the bore 6 of the casting 5 and is provided upon its upper surface with the teeth 9. One end of this bar is formed with a rectangular head 10 from the end face of which the spaced ears or studs 11 longitudinally project. Upon one end of the casting 5, the jaw members 12 are mounted, each of said jaw members having an upwardly extending arm 13 fulcrumed, as at 14, upon one side of the rectangular casting. In the upper end of one of the arms 13 a screw 15 is threaded, said screw having a reduced portion 16 terminating in a circular head 17 which is adapted to bear against the inner face of the opposed arm 13. The other or outer end of the screw 15 is provided with suitable means, indicated at 18, whereby said screw may be conveniently turned or rotated. It is apparent that, by simply adjusting this screw to engage the head 17 against the confronting arm 13, the jaws may be forced inwardly toward each other.

The body casting 5 is formed with upwardly projecting spaced ears 19 which are connected by a fixed transverse rod or axle 20. A gear 21 is journaled upon this axle and meshes with the teeth 9 of the rack bar 8. The arms 22 of a yoke member are loosely engaged upon the ends of the axle 20 and to said yoke a suitable handle 23 is connected. The yoke member carries a gravity pawl 24 to engage the teeth of the gear 21 and rotate the same when said yoke is moved in one direction. A second pawl, indicated at 25, is mounted upon the body casting 5 on the opposite side of the gear and also engages the teeth thereof to prevent a retrograde rotation of the same.

A second pair of clamping jaws 26 are provided, each of which is also formed with an upwardly extending arm 27 terminating in a suitable handhold, and from each of these arms, a lug 28 projects inwardly. These lugs have loose pivotal engagement upon the respective pins or studs 11 projecting from the end face of the head 10 on the rack bar 8.

In the drawing, I have shown a well-known type of joint member for the abutting ends of rails, which consists of the chair plate C with which the fish plates P are integrally formed, said plates extending upwardly over the rail base and against the opposite sides of the web of the rail

indicated at R. Upon each of the fish plates, a reinforcement is formed and these reinforcements serve as abutments against which the jaws 26 are adapted to engage.

5 In the practical operation of the device, the same is mounted upon one of the rails, as illustrated in Fig. 1 of the drawing. Frequently the joint member, after a long period of use, becomes so tightly engaged
10 against the rail ends that it is quite difficult to remove the rail or disconnect the same from the joint member, and it is with a view to providing a simple and effective means for loosening the joint member that the present invention is devised. After adjusting the screw 15 so as to securely clamp the jaws 12 against the opposite sides of the rail, the jaws 26 are arranged against the outer faces of the fish plates P contiguous
15 to the reinforcement thereon. The handle member 23 is now oscillated, and in each movement of the same in one direction, the pawl 24 engaging the gear 21 rotates the latter and imparts a rectilinear movement
20 to the rack bar 8, thus causing the jaws 26 to exert pressure against the abutments and thereby shift the joint member and loosen the connection of the fish plates with the rail. After thus loosening the joint member,
25 the two rail sections can be readily removed.

From the foregoing description, taken in connection with the accompanying drawing, the construction, manner of operation
30 and several advantages of the invention will be clearly and fully understood.

The device may be very easily and quickly arranged in its operative position upon the rails and requires but little manual exertion in order to operate the same and readily shift the fish plates into position so that the rails can be removed.

While I have herein disclosed a particular form, construction and mounting of the jaw members, it is apparent that in this particular, the device is capable of considerable modification.

I also reserve the privilege of adopting various other changes in the form, propor-

tion and arrangement of the several coöperative elements of the invention and I, therefore, wish it to be understood that I reserve the privilege of adopting all such legitimate changes as may be fairly embodied within the spirit and scope of the 55 invention as claimed.

Having thus fully described my invention, what I desire to claim and secure by Letters Patent is:—

1. A device of the character described including a body member means carried by said member for anchoring the same in position upon a rail tread, said member having a longitudinal bore, a rack bar longitudinally movable through said bore, 60 means on said bar adapted for engagement against abutments on joint fish plates, and manually operable means carried by the body member and coöperatively engaged with the rack bar to move the same and 65 cause the means thereon to exert a pressure against the abutments and shift the fish plates longitudinally of the rail.

2. A device of the character described including an elongated body member having a longitudinal bore and provided on one end with obliquely disposed anchoring braces, means on the other end of the body member to clamp the same in position upon a rail tread, a rack bar longitudinally movable in the bore of said body member, a gear mounted upon the body member and coöperatively engaged with the teeth of the rack bar, opposed jaws mounted upon one end of said rack bar and adapted for engagement against abutments on joint fish plates, and means mounted upon the body member to manually rotate said gear and actuate said rack bar to cause the jaws thereon to exert a pressure against the fish 80 plate abutments and shift the fish plates longitudinally of the rail.

In testimony whereof I hereunto affix my signature in the presence of two witnesses.

MIKE DEAK.

Witnesses:

FRANK SCURICH,
M. F. LARKIN.
